TREATMENT OF HYDROCARBON OILS

Jacque C. Morrell, Chicago, Ill., assignor to
Universal Oil Products Company, Chicago, Ill.,
a corporation of South Dakota

No Drawing. Application December 19, 1931,
Serial No. 582,152

3 Claims. (Cl. 196—36)

This invention relates to the treatment of hydrocarbon oils and more particularly is directed to the treatment of petroleum distillates, especially those resulting from the conversion of

5 relatively higher boiling hydrocarbons into lower boiling hydrocarbons by treatment at elevated temperatures, commonly referred to as cracked distillates, by subjecting the same while in vapor form to the action of solutions of acid sulphates 10 alone or in direct combination with sulphuric acid. More particularly, the invention relates to the treatment of the said hydrocarbons while in the vapor form with solutions containing sulphuric acid and a salt of an alkaline earth metal 15 such as the sulphates of calcium, barium, magnesium and strontium. Presumably, these salts are present as acid sulphates and it is desirable that they always be present in the form of the acid sulphate, i. e. with excess sulphuric acid. 20 Where an insufficient quantity of the sulphate of the alkaline earth is dissolved to control the concentration of the sulphuric acid, the sulphates or acid sulphates of the alkali metals such as sodium, potassium and ammonium may be added 25 in addition.

Petroleum distillates, especially cracked distillates, contain undesirable compounds, presumably of a highly unsaturated character, which render them unstable with respect to color, gum- 30 forming properties and knock rating. Such distillates tend to deposit polymer or gum-like substances while in storage, causing a drop in color which may render the product unsaleable. The development of gums may also prevent proper 35 operation of the motor by plugging or gumming up the fuel feed lines, carburetor, valves and other parts of the motor. Other objectionable compounds such as those of sulphur, nitrogen and the like, may be present in such distillates, and it is 40 among the objects of this invention to remove or reduce to a minimum, the objectionable substances present in hydrocarbons and more particularly, in petroleum distillates.

One of the most important and most desirable 45 developments in petroleum refining is the direct production of a marketable distillate from the cracking process. Many attempts have been made to employ refining agents for this purpose, particularly directed towards the use of sulphuric acid which for the most part have been 50 unsuccessful because they have failed to take into consideration the physical and chemical properties of sulphuric acid under the conditions of refining. The use of sulphuric acid as a refining 55 agent antedates the drilling of the first oil well

in the United States, but heretofore, it has been most successfully applied as a refining agent to petroleum and its products while in the liquid state.

The following table taken from 1913 Edition of the Manufacture of Sulphuric Acid and Alkali by Lunge, a standard work on the subject, shows the relationship between the boiling point and concentration of sulphuric acid:

From the above table it is evident that at a given temperature and at each temperature, the sulphuric acid exists at a definite concentration and that irrespective of the concentration of the sulphuric acid feed into a system at a given temperature, if it is more dilute than that indicated by the concentration for the corresponding temperature it will concentrate to the given concentration. For example, if an approximately 8% solution of sulphuric acid is fed into a tower, the average temperature of which is approximately 360° F., neglecting the partial pressures of the steam and oil vapors, the sulphuric acid introduced will concentrate to approximately 75% and under these temperatures, such a concentration of sulphuric acid will immediately attack and destroy the unsaturated hydrocarbons in the immediate vicinity, resulting in an off-colored overhead product of high gum content and in a charring of the derivatives of sulphuric acid in the hydrocarbons, plugging up the column and rendering the process inoperative. The

above indicates only approximately the conditions existing in the tower, but is sufficient to illustrate the trend and direction of the reaction and explain why previous attempts to refine in 5 the manner described, have been unsuccessful. It is well known that concentrations of sulphuric acid which may be even substantially non-reactive at ordinary temperatures are highly destructive in their reactions at elevated temperatures. 10 Hence, while it is desirable to treat petroleum distillates in the vapor state in order to avoid the expense of redistilling the product, it is imperative that a method of treatment be provided which will enable one to definitely control the 15 concentration and consequently the rate of reaction and kind of reaction at the elevated temperatures of treatment. The present invention accomplishes this aim in a new and novel manner which will be hereinafter more fully described.

In a specific aspect the invention comprises treating hydrocarbon vapors, especially cracked hydrocarbon vapors, with an aqueous solution containing dissolved therein sulphuric acid and 25 a sulphate of an alkaline earth metal which is presumably present in the form of the acid sulphate.

In effecting the operation of the invention, hydrocarbon vapors from any source, for example, 30 direct from a cracking process, and in general from a distillation process, including vapors from atmospheric distillation or hydrocarbon vapors from rerun stills, may be passed counter-current or concurrent to the solution containing the acid 35 sulphate and the sulphuric acid. The treating solution may be introduced in the form of a spray, atomized or otherwise introduced and employed in such manner as to give the most efficient contact of treating agent and vapors undergoing treatment. Under some conditions, the hydrocarbon vapors may be bubbled through a pool 40 or pools of the treating agent preferably feeding in fresh reagent and withdrawing sludge continuously. In the countercurrent operation the vapors may be withdrawn from the top of the treating tower and may be condensed or fractionated and condensed, preferably subjecting the treated 45 hydrocarbons to treatment with alkalis or combination washing and alkali to remove sulphur dioxide and possibly some entrained treating agent. In the concurrent method of operation the vapors, reflux condensate and sludge may be passed through a separator, withdrawing the vapors and condensing as described, and separately withdrawing the sludge and/or products of reaction together with unused treating agent and reflux condensate if present.

Steam may be introduced into the column during 50 the treatment in order to maintain an equilibrium between the dissolved substances in the water, namely, the acid sulphate and sulphuric acid.

The sludge may be used directly by recirculating to the treating column. The acid sulphates 55 may be recovered by dilution and treatment of the sludge with water and subsequent purification and evaporation of the solution.

The process may constitute the sole step of 60 the process in the refining of the hydrocarbons or may be combined with other treatments either applied before or after the process of this invention. For example, the vapors from the treating tower may be subsequently passed through a filter or series of filters containing inert filtering agents, adsorbents, solid alkalis, such as lime,

caustic or mixtures of these and the like, catalytic materials such as metals and metallic oxides, solutions of alkalis, and the like. Preferably the vapors are fractionated before passing to the treating stage and may be fractionated after passing to the treating stage. Prior treatments of the hydrocarbons with other reagents, either in the vapor or liquid phase, or subsequent treatment of the condensed liquid may be applied.

For example, the condensed product may be sweetened by treatment with plumbite solutions, 80 solutions of copper salts or other metallic salts alone or in combination with auxiliary chemical treatments with acids, and the like or with filtering agents such as fuller's earth and like adsorbing agents. Sludges from the treating reagent may be reused or regenerated.

As specific examples of reagents used in the 85 present invention where calcium sulphate is employed, an approximately 4% solution in a 10% solution of the sulphuric acid may be employed. A solution containing approximately 18% of barium sulphate and approximately 80% of sulphuric acid may be employed. Strontium sulphate will 100 give a similar solution and magnesium sulphate will dissolve to a greater extent. For some conditions of treatment the alkaline earth metals, sulphates or equivalent salts do not dissolve to a sufficient extent to permit the required 105 control of the concentration of the sulphuric acid under the conditions of treatment.

In order to obtain exact control of the solution, it is preferred in many cases to add to the sulphuric acid a sulphate or acid sulphate, particularly a sulphate of the alkali metals such as sodium, potassium or ammonium sulphate, in addition to the sulphates of the alkaline earth metals. Generally, the initial concentrations of sulphuric acid employed, vary from 30 to 60% 110 and the initial concentrations of salts employed vary from 5 to 20%, the remainder being water.

As an example of results obtainable by the 115 operation of the process of my invention, and of the operating conditions thereof, the following may be cited. A California cracked distillate containing approximately 0.45% sulphur is subjected to treatment in the vapor form at 120 approximately 300° F. with a solution containing approximately 50% of sulphuric acid, 10% of calcium sulphate, 15% of ammonium acid sulphate and 25% of water. The resultant product may have a color of approximately 28 which is stable on exposure to sunlight, a gum content of approximately 15 mgs. per 100 cc. and a 125 sulphur content of approximately 0.32, the original distillate having a dark brownish-yellow color and showing a gum content of approximately 600 mgs. per 100 cc. by the copper dish method.

Similar results may be obtained when the calcium sulphate is increased relative to the ammonium sulphate concentration. Sodium acid sulphate may be employed instead of ammonium acid sulphate with good results. Mixtures of 130 strontium sulphate and barium sulphate as well as other mixtures of the alkaline earth metals likewise give good results.

I claim as my invention:

1. In a process for the refining of hydrocarbon 145 oils, the improvement which comprises subjecting the said hydrocarbon oils while in heated vaporous condition to reaction with an aqueous solution of sulphuric acid in which has been dissolved at least 4% of a sulphate of an alkali 150

metal, the amount of acid originally contained in the solution exceeding the amount of the sulphate added thereto.

2. In a process for the refining of cracked hydrocarbon oils, the improvement which comprises subjecting the said cracked hydrocarbon oils in heated vaporous condition to reaction with an aqueous solution of sulphuric acid in which has been dissolved at least 4% of a sulphate of an alkaline earth metal and a sulphate of an alkali metal, the amount of acid originally con-

tained in the solution exceeding the amount of the sulphate added thereto.

3. A process for the refining of hydrocarbon oils which comprises subjecting the hydrocarbon oils while in heated vaporous condition to the action of an aqueous solution containing from 10 to 60% of sulphuric acid and in which has been dissolved from 5 to 30% of alkaline earth metal sulphate and alkali metal sulphate.
